US00D674624S

(12) **United States Design Patent**
Kassab et al.

(10) **Patent No.:** **US D674,624 S**
(45) **Date of Patent:** **** Jan. 22, 2013**

(54) **STRUCTURALLY SUPPORTING SHIPPING
AND DISPLAY PACKAGING ASSEMBLY**

(75) Inventors: **Salem Kassab**, Commerce Township, MI (US); **Derick Kassab**, Wolverine Lake, MI (US)

(73) Assignee: **SFD Manufacturing, LLC**, Farmington Hills, MI (US)

(**) Term: **14 Years**

(21) Appl. No.: **29/427,055**

(22) Filed: **Jul. 13, 2012**

(51) **LOC (9) Cl.** **06-06**

(52) **U.S. Cl.** **D6/476**

(58) **Field of Classification Search** D6/434, D6/449-450, 470, 476-479, 490-492; 108/59-61; 211/34-36; 312/265.1-265.2, 265.3-265.4

See application file for complete search history.

(57) **CLAIM**

The ornamental design for a structurally supporting shipping and display packaging assembly, as shown and described.

DESCRIPTION

FIG. 1 is a perspective view of the present design; FIG. 2 is a front plan view, a corresponding rear view being a mirror image thereof; FIG. 3 is a right side view, a corresponding left side view being a mirror image thereof; FIG. 4 is a top view; and, FIG. 5 is a bottom view.

The broken lines are for the purpose of illustrating the environment of the design only and form no part of the claimed design.
